SIGNALING SYSTEM AND APPARATUS

Foster E. Weld, Newton Highlands, Mass., assignor to The Gamewell Company, Newton, Mass., a corporation of Massachusetts

Application February 11, 1933, Serial No. 656,288

12 Claims. (Cl. 177—367)

This invention relates to signaling systems and particularly to signaling systems utilizing code signal transmitters.

Such signaling systems ordinarily comprise a current source, manifesting apparatus, and a plurality of signal transmitting stations each having circuit breaking mechanism, and, in the instance of the usual fire alarm transmitters, electromagnetically controlled non-interference and succession mechanism connected in a normally closed metallic circuit.

In such systems, a break anywhere in the normally closed circuit renders all transmitting stations in such circuit ineffective for transmitting an intended signal to manifesting apparatus at a central office.

Various means have been suggested, heretofore, to make use of the ground as a common conductor from the current source at the central office to the transmitting stations, so that, in the event the circuit is broken, a current path may be established from the current source over one side or the other of the broken circuit through central office manifesting apparatus, the signal contacts and non-interference magnet in the transmitting station and then through the ground back to the current source. Such means have been objectionable for one reason or another, however, and have not been adopted for use with transmitters already in service, it being considered preferable to replace the transmitters by other mechanism adapted for the purpose, rather than to modify the existing transmitters to include such prior ground control means.

It is therefore an important object of this invention to provide simple and inexpensive means for automatically rendering the ground connection at a transmitting station effective for signaling over either side of a broken line, which means may be readily added to the great majority of transmitters now in common use.

In the means heretofore employed for the control of a ground connection in a transmitter, additional contacts operated in various ways by the transmitter mechanism have been used. For reasons well understood by those skilled in this art such ground control contacts of any transmitter should be closed only during the transmission of a signal therefrom and may, therefore, remain unused for long periods of time. The force necessary to close such contacts so as to assure a positive, low resistance connection, following such long periods of disuse, is usually greater than that available for the transmitting mechanism.

It is, therefore, another object of this invention to provide means whereby the normally open ground connection at the transmitter is closed by a single contact arranged to be closed by movement of the manually operated transmitter starting lever to starting position.

In some types of prior art transmitters having electromagnetic non-interference mechanism, the ground connections have been so applied that only one-half of the non-interference magnet winding has been effective when such transmitters were conditioned to utilize their ground connection for the transmission of their signals over one side or the other of a broken line. This is objectionable because the circuit resistance over one side of the line and through such grounds as are ordinarily available at signal boxes may be substantially greater than the normal metallic circuit resistance, and when only one-half of the magnet winding is effective during such circuit condition, energization of such magnet may be insufficient to assure complete effective transmission of the signal.

Therefore, another object of this invention is to so apply the ground connection at the transmitter that the entire winding of the non-interference magnet (which may also control succession mechanism) will at all times be in whatever current path is then effective for control by the signaling contacts.

Another object is to so apply a ground connection that the single pair of signaling contacts universally provided for signaling over the normally closed metallic circuit, will also be effective for signaling over one side or the other of a broken circuit.

A further object of the invention is the provision of a signal circuit having a transmitter therein and apparatus which, in the event a part of the normal signal circuit is faulty, as interrupted, automatically selects a sound part of the circuit for the transmission of its signal thereon.

Another object of the invention is the provision of a signaling system including a signal circuit and a transmitter therein and an asymmetric conductor so arranged that, when a part of the signal circuit is faulty or broken, the signal is caused to be directed through the unbroken portion of the signal circuit.

A further object is generally to improve the construction and operation of signal circuits and signal transmitters.

Fig. 1 is a diagrammatic view of a signaling system embodying the present invention.

features of the circuit of Fig. 1 with much of the apparatus of Fig. 1 omitted.

As herein illustrated, the signaling system is adapted especially, although not restricted to the 5 transmission of fire alarm signals and shows at B a fragmentary front elevation of a signaling train of a well-known and widely used form of fire alarm signal transmitting station or "box", such, for example, as that shown by Patent No. 10 1,664,952 to Nathan H. Suren, with an illustrative embodiment of this invention applied thereto, together with diagrammatic representations of the circuit controlling means of two other, or more, similar stations at A and C, and central office signal responsive apparatus at M¹ and M² and a current source S.

The signaling train of station B may be briefly described as comprising a main wheel 21, arranged for actuation by a spring 22 to drive the 20 code wheel 23. A detent member, comprising the lever 26, is arranged to cooperate with the flange 27 carried by the wheel 21 in the usual manner, so that said mechanism is normally held at rest and so that momentary elevation of said lever 25 will condition said train to permit a desired cycle of the operation thereof in the course of which said wheel 21 will so rotate as to cause a suitable number of revolutions of the code wheel 23, and hence rounds of the intended signal; following 30 which said lever may move downwardly to its normal position and thereby cause the train to be again brought to rest, unless such movement of said lever is prevented by manipulation of the manually operable, so-called "pull handle" 28, 35 which is provided for facilitating actuation of the lever 26 to release the mechanism, or by other means such as will be presently described.

The signaling lever 29 is pivotally supported at 30, and carries the projection 31 for cooperation 40 with the code wheel 23. The tail 32 is carried by and moves with said lever 29; the free end of said tail being arranged for cooperation with the pin 33 carried by the wheel 21 for holding said lever 29 away from said code wheel when the mechanism is at rest and also immediately after the starting thereof, until the first tooth or projection of said wheel has moved into the path of said projection 31.

The lever 40 is pivoted at 41 and carries the 50 armature 42 at the end thereof. The opposite end of said lever 40 carries a rearwardly extending projection 43 for cooperation with the pin 44 carried by the wheel 45 which rotates with the code wheel 23. As indicated by the dotted line 55 45a directly above the left hand edge of the pin 44, said projection is so formed that, when the lever 40 is in the position which it occupies when the armature 42 is in fully attracted position, said pin may pass to the right of said projection and 60 said projection extends to the left of said dotted line coextensively with the contour of the lever 40, as shown, so that when said lever is in the position which it occupies when the armature 42 is in fully retracted position, said projection will 65 be disposed within the arc described by the revolution of said pin around the axis of the wheel 45 and will thus avoid engagement thereby, and so that when said lever occupies an intermediate position, to which it may be moved as is herein- 70 after more fully explained, said projection will be in the path of said pin for engagement thereby to move said lever to carry the armature 42 to its normal attracted position.

The pin 46 is carried by the lever 40 in such 75 position as to be adapted for cooperation with

the free end of the detent lever 26 as is herein-after more fully explained, and the retractile spring 47 is suitably connected with said lever 40 and is of such strength as to prevent movement of said lever in response to the pull of the 5 electromagnet when the armature 42 is in fully retracted position.

The signaling contacts 48 and 49 are arranged for actuation in the usual manner by the signaling lever 29; and the usual protective shunt 10 contacts 51 and 52 are carried by the insulating blocks 53 and 54, respectively; said block 53 being fixed upon the frame plate 50 and said block 54 being so mounted upon the lever 26 that when said lever is positioned for restraining operation 15 of the signaling train the contact 52 will engage the contact 51 and when said lever is positioned to permit operation of said train said contacts will be separated.

The faces 55 and 56 and the shoulder 57 are 20 so formed in the free end of the lever 26 that, when said lever is positioned for restraining operation of the signaling train, said face 55 will so engage said pin 46 as to prevent movement of the lever 40 from attracted to retracted position; said face 56 is so positioned that movement of the detent lever 26 from its fully elevated position toward the position where it will cause the running of the signaling train to be arrested will cause said face to act through the 30 pin 46 to move the lever 40 so as to bring the projection 43 carried thereby into the path of the pin 44; and the shoulder 57 is so positioned that, when the pin 46 is resting against the face 55, said shoulder will engage said pin during move- 35 ment of the detent lever 26 away from its fully elevated position before such movement has proceeded to a point such as will cause the running of the signaling train to be arrested.

A pin 58 is carried by the armature lever 40 40 in such relationship to the extension 59 forming part of the signaling lever 29 that said signaling lever may assume the position which permits the contact 48 to move away from the contact 49 only while said armature is in its normal or 45 attracted position, and such that said armature lever will be permitted to move to its abnormal or retracted position only while the contact 48 is in engagement with the contact 49.

The electromagnet 100 is cooperatively associated with the armature 42 for controlling non-interference and succession mechanism in a manner well understood by those skilled in this art and has one end of its winding connected through conductor 109 to the signaling contact 49, and 55 the other end of its winding connected through conductor 111 to the protective shunt contact 51, and thence through conductor 108 to the main line terminal post 113. The other main line terminal post 112 is connected through conductor 107 to signaling contact 48 and also through conductor 118 to the protective shunt contact 52.

From the foregoing it will be seen that a signaling current path is provided from the post 112 through conductor 107 to signaling contact 65 48, thence through said contact and through contact 49, conductor 109, winding of magnet 100, conductors 111 and 108 to the other post 113; and that, when the detent lever 26 is normally positioned, a low resistance or shunt path is provided in parallel with said signaling path from said post 112, through conductor 118 protective shunt contacts 52 and 51, and conductor 108 to post 113.

The signal transmitting apparatus thus far 75

described is the signaling train of a well-known form of so-called "perfect non-interference and succession" fire alarm box, and is here shown and described as typifying one of the forms of 5 signal transmitting apparatus to which this invention may be applied, and it will be understood by those skilled in this art that this invention is suited for corresponding or similar application to other forms of signaling trains.

10 The three transmitting stations A, B, and C, are serially connected in a normally closed metallic circuit comprising conductors 116, 117, 119, and 120, leading to the terminals T¹ and T² of the central office. A unidirectional current 15 source, such as the battery S is provided at the central office. One terminal of such source is connected to the central office terminal T¹ through conductor 121, signal manifesting apparatus, such as the register M¹, and conductor 20 122. The other terminal of the source S is connected to central office terminal T² through conductor 123, signal manifesting apparatus, such as the register M², and conductor 124. It should be understood that means for supplying 25 a unidirectional current, such, for example, as an alternating current rectifier or a direct current generator, may be substituted for the battery indicated at S; and that other signal manifesting apparatus such, for example, as bells, 30 lamps, etc., may be substituted for, or included in the circuit with, the registers M¹ and M².

In accordance with this invention means are provided at each transmitter, operative in the event one side of the signal circuit is broken, 35 for automatically causing the signal of the transmitter to be transmitted through ground and the unbroken side of the signal circuit. Said means includes asymmetric conducting media such as the rectifying unit R that is provided 40 at each transmitting station and is connected to the main line terminal posts 112 and 113 thereat in such manner as to oppose current flow therethrough in the direction in which current is induced by the potential of the source S, being 45 here shown as opposing current flow from post 113 to post 112. The asymmetric conductor or rectifying unit R may be of any well-known form such, for example, as the so-called "dry disc" type, and should have a center tap or connection 50 intermediate the terminals thereof, as indicated at 130. This connection divides the rectifier R into two serially connected sections 131 and 132 which are conductive in the same directions, the purpose of which will be explained 55 fully hereinafter.

It should be understood that while rectifying unit R may consist of any one of the more or less well known types of asymmetric conductive equipment,—in any event, it should freely permit current flow therethrough in one direction and substantially exclude current flow in the other direction between the end or extreme terminals thereof, and its asymmetric conductive characteristic should be effective at both sides 65 of its intermediate terminal or connection.

Each transmitter is provided with normally open ground contacts at 135 and 136. Contact 136 is mounted on said insulating block 53 and contact 135 is so carried by said insulating block 70 53 that when the lever 26 is positioned to permit operation of the signaling train said contact 135 will engage contact 136. It should be noted that the ground contacts 135 and 136 are closed by the manual operation of the transmitter pull handle 28 and are of such proportions and ar-

angement as to assure a positive low resistance connection when closed. The contacts are so arranged and located that they can be applied readily to existing transmitters for operation in accordance with this invention. 5

The center tap or connection 130 of the asymmetric conductor or rectifier R is connected through conductor 133 to ground contact 135, and the other ground contact is connected through conductor 137 to the terminal 138 which terminal 10 is connected to the ground or other suitable common return conductor.

The central office current source S also has a center tap or connection 125 electrically intermediate to the terminals thereof which connection is permanently connected to the ground or other common return conductor. 15

If the resistance of the metallic circuit outside of the central office terminals T¹ and T² is low in comparison to the resistance of the manifesting apparatus at M¹ and M², as would frequently be the case in actual practice, there will be little if any current flow through the ground or common return conductor G because of a ground connection at any transmitting station while the 25 outside line is closed. Hence, no responsive apparatus is deemed necessary in the ground lead from the center connection 125 of the current source S, inasmuch as the apparatus at M¹ and M², as will be more fully explained hereinafter, 30 will respond to signals from any station connected in the outside line under all circuit conditions except from stations located between two breaks, two ground connections, or between a ground connection and a break in the outside metallic circuit, or from stations shunted by a short-circuit around the terminals thereof, such, for example, 35 as might be caused by a connection between the wires leading to such stations.

The operation of a transmitting station such 40 as station B, while the circuit is normally conditioned, is substantially the same as that of a well-known type of perfect non-interference and succession fire alarm signaling box, which is well understood by those skilled in this art, and will therefore not be here described in detail. It 45 should, however, be noted that, throughout activity of station B, the normally open ground contacts 135 and 136 are closed, thereby establishing a current path from the center connection 130 of the asymmetric conductor or rectifier R to the ground terminal 138. Although this ground current path does not affect operation of the transmitter B or response thereto of manifesting apparatus M¹ or M² under normal circuit 50 conditions, it is effective during abnormal circuit 55 conditions as will be described hereinafter.

In the event that the normal "all metallic" current path is broken, as by rupture of conductor 116 or 117, and the transmitting mechanism at station B is started by actuation of pull handle 28,—the operation is as follows:

Detent lever 26 will be elevated, thereby moving contact 52 away from contact 51 so as to break the protective shunt around the winding 65 of magnet 100 and the signaling contacts 49 and 48 as well as around the rectifier R. Such movement of the lever 26 by the pull handle 28 will also raise contact 135 into engagement with contact 136, thereby closing the normally open 70 current path from the connection 130 of rectifier R to the ground terminal 138.

Closing of ground contacts 135 and 136 completes an emergency current path from the positive terminal of source S through conductor 123, 75

register M^2 , conductor 124, to terminal T^2 , through conductor 120, station C and conductor 118 to post 113 of station B, thence through conductors 108 and 111, winding of magnet 100, conductor 109, signaling contacts 49 and 48, and conductor 107 to post 112, thence through section 131 of rectifying unit R to the center connection 130 thereof, thence through conductor 132, ground contacts 135 and 136 and conductor 137 to the ground terminal 138, and thence through the ground or other common conductor to the center connection 125 of source S.

From the foregoing it will be seen that the current path established by the closing of contacts 135 and 136 serially includes one-half of the current source S, the manifesting device M^2 and the entire winding of magnet 100 and the signaling contacts of station B.

The transmitting mechanism of station B thereupon proceeds to transmit its signal by the breaking and making of this emergency current path, in the same manner as when signaling over a normally closed all metallic circuit, which may be summarized as follows:

25 When the detent lever 26 has been sufficiently raised, the signaling train will start running, and thereby rotate the code wheel 23. Such rotation of the code wheel 23 will bring the first of the code teeth carried thereby into the path of the projection 31 of the signaling lever 29 and, thereupon, the pin 33 will be withdrawn from the path of the tail 32 of said signaling lever, so as no longer to prevent said lever from following the outline of said code wheel. If the electromagnet 100 remains energized until the first tooth of the code wheel 23 is withdrawn from the path of the projection 31, the signaling lever 29 will be moved downwardly in response to the tension of the contact 48, and said contact will thereupon move 40 away from the contact 49; thereby interrupting the current path through the signal responsive apparatus at M^2 and magnet 100. Upon such circuit interruption, said responsive apparatus M^2 will act in response thereto, but the armature 45 42 will not be permitted to move away from the magnet 100 because the downward movement of the signaling lever 29, incident to the circuit interruption, carried the extension 59 thereof into the path of the pin 58 and thereby held the lever 50 40 from movement in response to the retractile spring 47 upon de-energization of the magnet 100. It will be understood that the circuit will be alternately closed and broken in accordance with the outline of the code wheel 23 so as to correspondingly cause the manifestation of the intended code signal by the responsive apparatus 55 at M^2 .

After a predetermined cycle of the operation of such train (usually four so-called "rounds" or 60 revolutions of the code wheel 23) the detent lever 26 will return to its normal position and thereby carry the ground contact 135 down out of engagement with its cooperating contact 136 and thus restore the ground connection to its normal 65 open circuit condition.

The train will be brought to rest thereafter as soon as the wheel 21 has reached the position which causes the pin 33 to engage the tail 32 of the signaling lever 29 and thereby cause said lever 70 to move the signaling contact 48 to its normal position.

In the event that the normal "all metallic" current path is broken on the other side of station B, as by rupture of conductor 119 or 120, and the 75 transmitter mechanism at station B is then start-

ed by actuation of pull handle 28, the operation is as follows:

The shunt contacts 51 and 52 will be opened and the ground contacts 135 and 136 will close the normally open current path from the connection 130 of rectifier R to the ground terminal 138 in response to pulling of handle 28, as hereinbefore more fully explained.

Closing of ground contacts 135 and 136 completes an emergency current path from the center connection 125 of the current source S through the ground or other common conductor G, ground terminal 138 of station B, conductor 137, ground contacts 136 and 135, conductor 133 to the center connection of the asymmetric conductor or rectifier unit R, thence through section 132 of said unit to main line terminal post 113, thence through conductors 108 and 111, winding of magnet 100, conductor 109, signaling contacts 49 and 48, conductor 107, post 112, conductor 117, station A, 20 conductor 116, terminal T^1 , conductor 121, register M^1 , and conductor 122 to the negative terminal of the source S.

From the foregoing it will be seen that the current path thus established serially includes one-half of the current source S, the entire winding of magnet 100 and the signaling contacts of station B, and manifesting device M^1 .

The mechanism of station B thereupon proceeds to transmit its signal by the breaking 30 and making of this emergency current path, in the same manner as just described in detail in connection with a break in the other side of the line, except that such signal will be responded to by the responsive apparatus at M^1 instead of by 35 the apparatus at M^2 .

In the event that the transmitting mechanism at two stations, such, for example, as stations A and B, are started simultaneously at a time when the metallic circuit is otherwise normally 40 conditioned, the ground paths at such stations will be closed, thereby completing independent current paths from the active stations over the respective sides of the line whereby the complete signal from station A will be responded to by the 45 apparatus at M^1 and the complete signal from station B will be responded to by the apparatus at M^2 , in the following manner:

Closing of the ground contacts 135 and 136 at station B establishes an emergency signaling 50 path over the right hand side of the line corresponding to that described in detail in connection with operation when conductor 116 or 117 is broken. It will therefore be obvious that breaking of the left hand side of the metallic circuit by activity of the signaling contacts of station A cannot affect the response of apparatus at 55 M^2 to the signals from station B.

Correspondingly, closing of the ground contacts 135 and 136 at station A establishes an 60 emergency signaling path over the left hand side of the line similar to that described in detail in connection with operation when conductor 119 or 120 is broken, and it will therefore be obvious that activity of station B cannot interfere with 65 the response of apparatus at M^1 to the signals from station A.

Although the complete signals from two such simultaneously active stations will be completely responded to by the respective devices M^1 and 70 M^2 , should the mechanism at one of such stations complete its signal and open its ground path before the mechanism at the other station has completed its signal, the remaining portion 75 of such signal will be responded to by both regis-

ters M^1 and M^2 . For example, if the signal transmitted from station A is 121 and the signal from station B is 321, and the mechanism at both stations each transmit four complete rounds of their respective signals, the timing of the transmitting mechanism may be such that station A will complete its transmission of four complete rounds of signal 121 and open its ground path during the transmission of the last round of signal 321 from station B. The register or other responsive apparatus at M^1 will then respond to the remaining fragment of the signal from station B.

In the event that the transmitting mechanism at station A is started at a time when the metallic circuit is in normal condition and, after the apparatus at M^1 and M^2 has responded to a portion of such signal, the transmitting mechanism at station B is started, the response of apparatus at M^2 to the signal from station A will be terminated and such apparatus will thereafter respond only to the signal from station B until the complete four rounds of such signal has been transmitted; following which, the apparatus at M^2 will again respond to the signal from station A, if transmission of same has not been completed. For example, assuming that the signal from station A is 532 and the signal from station B is "21", and that each mechanism is arranged to transmit its signal four complete rounds, and further assuming that station A is started first and, after transmitting a portion of the first round of its signal, for example, "53" the transmitting mechanism station B is then started—the timing of the two transmitting mechanisms might be such that the record on the tape of a register at M^2 would show the number "53", then four rounds or repetitions of the signal "21" from station B, and then a fragment such as "22" of the later part of the third round of signal 532 from station A, followed by the number 532 representing the fourth complete round from station A. During such activity of these two stations, the tape of a register at M^1 would show only the four complete rounds of the signal 532 from station A.

If the numbers transmitted by the two stations A and B were nearer the same length, such, for example, as 321 and 324,—and the mechanism at station B is started after station A has transmitted, say one round; a register at M^1 will first record the complete four rounds of signal 321 from station A and then the remaining portion of the signal from station B, and a register at M^2 will first record that portion of the signal transmitted from station A before the mechanism at station B was started and then record the four complete rounds of signal 324 from station B.

In the event that, during concurrent activity of two stations, such, for example, as stations A and B as just described, the mechanism at a third station, as at station C, is started,—the closing of the ground path at such third station in response to the starting thereof will render intervening stations, such as station B, ineffective for causing response of apparatus at either M^1 or M^2 . The signal from station C will thereupon be responded to by the apparatus at M^2 and the apparatus at M^1 will continue to respond to the signal from station A.

The reason that intervening stations, such as station B, are rendered ineffective for causing response of apparatus at M^1 or M^2 is that such stations are not included in the emergency sig-

naling paths established by the stations, such as A and C, which are located in the circuit nearer to the central office terminals. Inasmuch as magnet 100 of station B is thus excluded from effective current paths, such magnet will not be energized. Armature 42 thereof will therefore fall away to fully retracted position and the non-interference and succession mechanism will function in the usual manner, which may be briefly described as follows:

Such retraction of armature 42 carries pin 58 into the path of extension 59 of the signaling lever 29 and thereby prevents movement of the signaling lever from circuit closing position. When the armature 42 of station B has moved to its retracted position, as just described, it will remain in such position until the end of a predetermined cycle of operation of the signaling train, whereupon the projection 62 carried by lever 26 enters notch 61 in flange 27 and said lever 26 will move away from its fully elevated position. Such movement of this lever, at a time when the armature is in retracted position, is arrested by engagement of the shoulder 57 formed in the end thereof with the pin 46 carried by the armature lever 40. This limited movement of lever 26 is not sufficient to permit opening of the ground contacts 135 and 136 or to cause the running of the signaling train to be arrested, but is such that engagement of the face 56 thereof with pin 46 will move lever 40 to a position where the projection 43 will be in the path of the pin 44.

Succeeding rotation of wheel 45 incident to running of the signaling train will cause the armature 42 to be moved approximately to its fully attracted position by the engagement of the projection 43 by the pin 44 and, if the mechanism at either station A or station C has completed transmission of its signal and opened its ground connection, armature 42 of station B will be held in its fully attracted position by energization of its magnet 100 and this mechanism will then again be effective for transmitting its signal to the responsive apparatus at either M^1 or M^2 , or both, depending upon which, if either, of station A or station C is still active. If station A is still active, the signal from station B will be responded to by the apparatus at M^2 only, until such time as station A completes its activity and removes its ground connection, whereupon the remainder of the signal from station B will be responded to by the apparatus at both M^1 and M^2 . Correspondingly, if station C is still active, the signal from station B will be responded to by the apparatus at M^1 only, until completion of the signal from station C and the removal of its ground connection, whereupon the remainder of the signal from station B will be responded to by the apparatus at both M^1 and M^2 .

If at a time when the metallic circuit is open between station B and the positive terminal of source S, the transmitting mechanism at station A is first started and the then mechanism at station B is started, the complete signal of station A will be responded to by the apparatus at M^1 and the non-interference and succession mechanism of station B will delay transmission of the signal from this station until station A has completed its signal and removed its ground connection. Station B will then proceed with the transmission of the complete four rounds of its signal, provided, of course, that the capacity of its main spring 22 has not been exhausted.

Such signal will also be responded to by the apparatus at M^1 .

If, however, under the conditions just referred to, the transmitting mechanism at station B is first started and then the mechanism at station A is started, the apparatus at M^1 will first respond to that portion of the signal from station B which is transmitted before the mechanism at station A is started, and then will respond to the complete signal from station A. The starting of the transmitting mechanism at station A will prevent energization of the magnet 100 of station B from the source S and the non-interference and succession mechanism thereat will then act to delay transmission of its signal until station A has completed its signal and removed its ground connection. Station B will then again proceed with the transmission of its signal, provided, of course, that the capacity of its spring 22 has not been exhausted, and the apparatus at M^1 will then respond to this signal also.

It will thus be seen that, under the condition just described, the tape of a register at M^1 would record a fragment of the signal from station B, then the complete signal from station A, and then would respond to the complete four rounds of the signal from station B.

From the foregoing it will be apparent that any number of stations may be started simultaneously or one after another on an otherwise normal metallic circuit and the apparatus at M^1 and M^2 will at all times respond to the two of such active stations which are nearest to the respective terminals of source S. The complete signals from all such active stations, in addition to possible fragments of some or all of such signals, will therefore be responded to, either by the apparatus at M^1 or the apparatus at M^2 , provided that the driving power for such stations does not become exhausted.

It will also be apparent that any number of stations may be started on one side or the other or on both sides of a break in the metallic circuit, and the complete signals from all such stations (in addition to possible fragments of some or all of such signals) will be responded to, either by the apparatus at M^1 or the apparatus at M^2 . The apparatus at M^1 will respond to the signals from all stations to the left of the break and the apparatus at M^2 will respond to the signals from all stations to the right of the break.

Although a non-interference and succession type of signaling mechanism has been selected for the purpose of illustrating this invention, such non-interference and succession mechanism is not essential to practicing of certain aspects of this invention.

Without such mechanism, the response of apparatus such as M^1 and M^2 to signals from stations under various conditions will be as hereinbefore fully described in connection with signaling apparatus such as illustrated at A, B, and C, except in cases where the signal from a given station is cut off from the control of the responsive apparatus, as by the concurrent activity of stations on respective sides thereof, or by a break in the metallic circuit on one side and an active station on the other side thereof. In such a case, the transmitting mechanism of the cut off station will continue to run and, after completing its intended cycle of signaling, will be brought to rest irrespective of whether it has had opportunity to transmit its signal to the responsive apparatus at the central office. If the active station or, if there are two such active

stations, one thereof between such cut off mechanism and the central office completes its signal and removes its ground connection before such mechanism has completed formulation of its signal, the remaining portion of such signal will then be responded to by appropriate one of the responsive devices at the central office.

It should be understood that the form of mechanism indicated by the accompanying drawing and hereinbefore described in detail, is selected for the purpose of illustrating this invention because it is familiar to those skilled in this art, and is susceptible of ready illustration and description. It is believed that, in view of the foregoing detailed description, the application of this invention to other prior art signaling mechanisms will be apparent to those skilled in this art.

I claim:

1. A signaling system comprising a signal circuit having a unidirectional current source therein, a signal transmitter in said circuit having normally closed contacts for formulating code signals, an asymmetric conductor in parallel with said contacts and opposed to the potential of said circuit, and means controlled by said transmitter for establishing connection between an intermediate part of said asymmetric conductor and an intermediate part of said current source. 30

2. A signal transmitter having actuating mechanism, signaling contacts operated thereby, an asymmetric conductor having serially connected sections connected in parallel with said contacts in opposition to the potential thereof, and grounding contacts operated by said mechanism for grounding said asymmetric conductor between sections thereof. 35

3. A signaling system comprising a signal circuit having a unidirectional current source therein provided with a grounded intermediate connection, manifesting apparatus in said circuit on both sides of said current source, a signal transmitter in said circuit having normally closed contacts for formulating code signals, an asymmetric conductor in parallel with said contacts and opposed to the potential of said current source, and grounding contacts controlled by said transmitter for grounding an intermediate part of said asymmetric conductor. 40 50

4. A signal transmitter having two normal line terminals and a third auxiliary terminal, a single pair of signal contacts, and means involving respective portions of an asymmetric conductor for providing connections between said auxiliary terminal and one and the other of said normal terminals of such character that said signal contacts are included both in the path effective for current flow in a predetermined direction between said auxiliary terminal and a certain one of said line terminals and in the path effective for current flow in a predetermined direction between said auxiliary terminal and the other of said line terminals. 55 60

5. A signal transmitter having two line terminals and a ground terminal, a normally closed metallic circuit current path between said line terminals, and a signaling contact operable to interrupt said path, in combination with asymmetric conducting media having terminals connected between said line terminals, and means for rendering said media effective for permitting signal transmitting current flow between said ground terminal and a point intermediate the terminals of said media. 70 75

6. A signaling system comprising a signal transmitter having a single pair of signal transmitting contacts, a non-interference winding in series with said contacts, a circuit including a unidirectional current source over which the signals of said transmitter are normally transmitted, and an emergency conductor connected with an intermediate part of said current source, said transmitter having means including an asymmetric conductor connected in shunt relationship to said contacts and winding and in such polarity as to be operative in the event of a break in a portion of said circuit for selecting for signal transmission from said transmitter the unbroken part of said circuit and said emergency conductor.
7. A signal transmitter having actuating mechanism and three terminals, a normally closed metallic circuit current path between two of said terminals, succession mechanism comprising an electromagnet serially included in said path and a circuit controller governed by said magnet having means for breaking said normally closed path, in combination with an asymmetric conductor connected between said two terminals, and means operable by said actuating mechanism for establishing a current path from a point intermediate the terminals of said conductor and the third one of said three terminals, said conductor being asymmetric in the same direction on both sides of said intermediate point.
8. A signal transmitter having actuating mechanism and a member for controlling the operation thereof, three terminals, a normally closed metallic circuit current path between two of said terminals, a code wheel and a signaling contact operable thereby to interrupt said path, in combination with an asymmetric conductor connected between said two terminals, and means operable by said actuating mechanism for establishing a current path from a point intermediate the terminals of said conductor and the third one of said terminals when said member is conditioned to permit operation of said transmitting apparatus, said conductor being asymmetric in the same direction on both sides of said intermediate point.
9. A signal transmitter having actuating mechanism and three terminals, a normally closed metallic circuit current path between two of said
- 10 terminals, and a signaling contact operable to interrupt said path, in combination with an asymmetric conductor connected between said two terminals, and means operable by said actuating mechanism for establishing a current path from a point intermediate the terminals of said conductor and the third one of said terminals, said conductor being asymmetric in the same direction on both sides of said intermediate point.
10. A signal transmitter having actuating mechanism, signaling contacts operated thereby, a succession magnet winding in series with said contacts, an asymmetric conductor in parallel with said contacts and winding, said asymmetric conductor being arranged to oppose intended current-flow therethrough between its terminals, and grounding contacts controlled by said mechanism for grounding an intermediate part of said asymmetric conductor, said conductor being asymmetric in the same direction on both sides of said intermediate part.
11. A signaling system comprising a signal circuit having a unidirectional current source therein provided with a grounded intermediate connection, a plurality of signal transmitters arranged in series in said circuit and each having a succession magnet winding and normally closed contacts for formulating code signals in said circuit, an asymmetric conductor in parallel with the winding and contacts of each signal transmitter, a separate ground connection for an intermediate part of each conductor, and contacts controlled by respective ones of said transmitters for controlling their associated ground connections, each said conductor being asymmetric in the same direction on both sides of said intermediate part.
12. A signal transmitter having actuating mechanism, signaling contacts operated thereby, an asymmetric conductor having serially connected sections connected in parallel with said contacts in opposition to the potential thereof, two line terminals and a ground terminal, connections for serially associating said signalling contacts between two of said terminals and for connecting the third of said terminals to said asymmetric conductor between sections thereof, and a contact operated by said mechanism for governing the effectiveness of the connection with said ground terminal.
